INVENTOR.
Alfred F. Reilly

BY
Robert E. Barry
ATTORNEY.

UNITED STATES PATENT OFFICE.

ALFRED F. REILLY, OF ATTLEBORO, MASSACHUSETTS, ASSIGNOR TO EVANS CASE COMPANY, OF NORTH ATTLEBORO, MASSACHUSETTS, A CORPORATION OF MASSACHUSETTS.

COMPACT.

Application filed November 12, 1927. Serial No. 232,396.

This invention relates to improvements in toilet accessories and more particularly to a novel compact of the general type now in vogue.

5 It is customary at the present time for ladies to carry a compact containing a mirror, powder and a powder puff. In such compacts, if loose powder is employed, it frequently sifts out of its compartment, and 10 presents an untidy appearance.

The primary object of the present invention is to provide a compact of simple and inexpensive construction, in which the powder is retained in place by a sifter disk 15 which normally holds the powder in position, but which when tapped lightly, will permit a small amount of powder to discharge on to the disk. The edge of the disk frictionally engages the wall of the compartment in which the powder is placed, so 20 that any movement of the powder past the edge of the disk is prevented.

Another object of the invention is to provide a compact of relatively slight thickness, and one in which the powder is prevented from working out of its compartment by a packing ring combined with a 25 sifter disk.

With the foregoing objects outlined and 30 with other objects in view which will appear as the description proceeds, my invention consists in the novel features hereinafter described in detail, illustrated in the accompanying drawing, and more particularly 35 pointed out in the appended claims.

Referring to the drawing,

Fig. 1 is a diametrical vertical sectional view of my improved compact.

Fig. 2 is a horizontal sectional view, taken 40 on line 2-2 of Fig. 1.

Fig. 3 is a perspective view of the bezel ring shown detached from the casing.

As shown in the drawing, the casing of my improved compact is quite shallow, and 45 consists of a circular concaved bottom 1, provided at its edge with an inwardly extending convexed ring 2, provided at its free edge with a downwardly extending annular cylindrical flange 3.

50 This casing is combined with a convex cover 4, which is hinged to the casing at 5, and may have its free end connected to the casing by any suitable fastening means. The cover may carry the usual mirror, rouge 55 cake, etc. (not shown).

Detachably mounted in the casing, is a bezel ring 6, which is split at 7, and is provided at its lower edge with an inwardly extending annular flange 8 which more or less snugly engages the upper surface of the bottom 1.

An outwardly extending annular flange 9 is provided at the upper edge of the bezel ring, and is adapted to move beneath the flange 3, when the ring 6 is expanded into position. The flanges 3 and 9 also engage each other more or less snugly to aid in preventing the powder from working out between these flanges.

Before the bezel ring is placed in the casing, a ring 10 of raw cotton or the like is fitted into the casing between its bottom and the rim 2, and then when the bezel ring is expanded into position, it tends to pack the ring 10, so that the latter prevents powder 70 from working up the outer surface of the bezel ring, even though the powder should work its way under the flange 8.

The bezel ring is formed of resilient metal, and due to this resiliency, the ends of the ring tend to overlap when the ring is not held in a position in which its ends abut, as at the point 7, and this resiliency of the ring is made use of to retain a sifter disk 11, in any position to which it has been moved 80 by the operator.

The sifter disk is preferably formed of a sheet metal stamping, and its edge frictionally engages the inner surface of the bezel ring 6. The central portion of the sifter 90 disk is depressed to form a cavity 12, into which powder may settle after passing through apertures 13 in the side wall of the concavity of the disk. The powder is shown at 14.

95 After the parts have been manufactured, and the casing has been provided with its cover 4, the parts are assembled by first placing the packing ring 10 in the casing; then inserting the bezel ring, and finally inserting the sifter disk. When the sifter disk is pressed into position, it causes the bezel ring to expand to the point where its ends come together in abutting relation, and at this time, the frictional engagement between the bezel ring and the sifter disk is such that the sifter disk will be held in any position to which it has been moved by the operator.

When it is desired to put powder in the 110

casing, the disk may be readily removed by inserting any pointed tool in one of the holes of the disk, and then moving the tool and disk through the opening in the casing.

5 After the powder 14 has been placed in the casing, the disk is replaced, and a sufficient space is left above the disk to receive a powder puff or the like.

From the foregoing, it is believed that the 10 construction, operation and advantages of the invention may be readily understood and I am aware that changes may be made in the details disclosed without departing from the spirit of the invention, as expressed in the 15 claims.

What I claim and desire to secure by Letters Patent is:

1. A compact comprising a casing, a bezel ring in the casing, packing surrounding said ring, and a sifter disk in the casing having 20 its edge frictionally engaging said bezel ring.

2. A compact, including a casing, a split bezel ring arranged in the casing, a packing surrounding said ring, and a sifter disk having 25 its edge frictionally engaging said ring.

3. A compact, including a casing, a split resilient bezel ring arranged in the casing, the ends of the bezel ring tending normally 30 to overlap, due to the resiliency of the ring, and a sifter disk arranged in the casing and having its edge frictionally engaging the ring and preventing the ends of the ring from overlapping.

35 4. A compact, including a casing having a flange, a split bezel ring arranged in the casing and having its upper edge abutting against said flange, and a sifter disk in the casing having a diameter substantially the same as the internal diameter of the ring.

40 5. A compact, including a casing, a bezel

ring detachably mounted in the casing and provided at its lower edge with an inwardly extending annular flange loosely engaging the bottom of the casing, and a sifter disk 45 arranged in the casing and having its edge engaging the inner surface of said ring.

6. A compact including a casing having a flanged opening, a resilient split bezel ring having an outwardly extending flange, at 50 its upper edge, and an inwardly extending flange at its lower edge, said outwardly extending flange engaging the flange of the casing and the inwardly extending flange engaging the bottom of the casing, and a 55 sifter disk arranged in the casing, and engaging the inner surface of said ring.

7. A compact including a casing, having a circular concaved bottom and an annular convex top wall, a split resilient bezel ring arranged in the casing and having its upper and lower edges engaging said top wall and bottom of the casing, a fibrous packing surrounding said bezel ring, and a sifter disk 60 arranged in the casing and engaging said bezel ring.

8. A compact comprising a casing, consisting of a circular concave bottom and an annular convex top wall, a split resilient bezel ring arranged in the casing and having 70 flanges at its upper and lower edges engaging respectively the top wall and said bottom, a packing of fibrous material surrounding said bezel ring, and a sifter disk arranged in the casing and having its edge 75 frictionally engaging the inner surface of said bezel ring, said sifter disk having apertures to permit powder arranged in the casing below the disk to discharge on to the disk.

ALFRED F. REILLY.
